UNITED STATES PATENT OFFICE.

JOSEPH B. LONG, OF CHICAGO, ILLINOIS.

DESIGN FOR A BODY FOR CADDIES.

SPECIFICATION forming part of Design No. 34,100, dated February 19, 1901.

Application filed August 20, 1900. Serial No. 27,505. Term of patent 3½ years.

To all whom it may concern:

Be it known that I, JOSEPH B. LONG, a citizen of the United States, residing at Chicago, in the county of Cook and State of Illinois, have invented and produced a new and original Design for the Body of a Caddy, of which the following is a specification, reference being had to the accompanying drawings, which are made a part of said specification, and in

10 which—

Figure 1 is a perspective view of the body of a caddy embodying the new design. Fig. 2 is an end elevation thereof.

The new design comprises a hollow body of 15 substantially rectangular shape in horizontal section, the interior of which is divided by vertical partitions A into a plurality of vertical compartments B. Its back and end walls are flat and vertical, while its front wall comprises a flat panel C, surmounted by a narrow 20 raised strip or rib D, extending from end to end of the body and having along its horizontal margin inturned flanges d. The top comprises a narrow flat portion E, adjoining the 25 back and disposed horizontally. The upper margins of the partitions A and of the ends F are inclined downward and forward and extend from the front margin of the strip E to

the top margin of the front of the body. The body is supported by legs G at its four corners. 30

The leading essential features of the design are the hollow body, having a flat front and flat ends, and the vertical partitions, dividing the interior of the body into a plurality of vertical compartments, the upper margins 35 of the partitions and ends of the body being inclined downward and forward.

Minor features of the design are the narrow raised rib D, extending along the upper margin of the flat front C, the inturned flanges d, 40 extending along the horizontal margins of the rib D, the narrow strip E, surmounting the partitions A and ends F and adjoining the back, and the legs at the four corners of a body having the general shape and configuration 45 above described.

What I claim as new, and desire to secure by Letters Patent, is—

The design for the body of a caddy substantially as herein shown and described. 50

Signed at Chicago, Illinois, this 30th day of July, 1900.

JOSEPH B. LONG.
